UNITED STATES PATENT OFFICE.

ERNEST B. NELSON, OF BURCHINAL, IOWA.

CORNCRIB CONSTRUCTION.

Application filed January 15, 1927. Serial No. 161,402.

This invention relates to the construction of corn cribs or the like, and has for its object the provision of a novel structure adapted to be mounted within a corn crib or the like, whereby to provide a ventilating space which will insure proper drying or seasoning of the corn or other products without danger of its souring or molding owing to lack of air.

10 An important object is the provision of a ventilating structure which may be quickly and easily mounted within an already existing corn crib or the like, the entire structure being knocked down and consequently therefore capable of being stored within a small space or transported from place to place easily.

Another object of the invention is to provide a ventilating structure in which the 20 parts are assembled simply by the interlocking feature thereof, it being unnecessary to use securing devices other than brackets adapted to be mounted upon the floor of the corn crib or other structure.

25 An additional object is to provide a structure of this device which will be simple and inexpensive in manufacture, easy to set up or take down, positive in action, efficient and durable in service, and a general improvement in the art.

With the above and other objects and advantages in view, the invention consists in the details of construction and the arrangement of elements to be hereinafter more fully 35 described and claimed, and illustrated in the accompanying drawings, in which:—

Figure 1 is a vertical cross sectional view taken through a corn crib equipped with the device, the device itself being likewise shown in section.

40 Figure 2 is a longitudinal section taken on the line 2—2 of Figure 1.

Figure 3 is a detail cross sectional view taken through the ventilator structure.

45 Figure 4 is a detail sectional view showing the manner of mounting the same upon the floor.

Figure 5 is a side elevation of one of the uprights.

50 Figure 6 is a detail cross sectional view taken at the top of the ventilator structure, and

Figure 7 is a detail elevation of one of the spreaders.

55 Referring more particularly to the draw-

ings, the letter A designates, generally, a corn crib or the like, which may be of any desired construction, but which is here, for the sake of illustration, represented as including a floor B mounted upon joists C supported on sills D. Suitable uprights E rise from springers F on the floor and carry transverse members G which support the rafters H upon which the roof I is mounted. The usual slats J are secured to the various uprights E for defining the walls. As a matter of fact, there are no limitations whatsoever as to the structure of the crib itself inasmuch as it may be anything desired, the invention pertaining only to the ventilating means to be described.

In carrying out the invention, I provide a ventilating structure designated generally by the numeral 10, this ventilator structure including spaced pairs of upright supporting brackets 11 which may, in actual practice, be formed as elongated metallic strips or bars cut at spaced intervals, as indicated at 12, to define tongue members which are bent outwardly and in an angular shape to define supporting brackets 13. Between the tongue members or brackets 13, the uprights 11 are formed with keyhole slots 14 through which are inserted spreaders 15 of rod-like form provided at points spaced from their ends with grooves 16 defining reduced necks 17. The members 11 are held in the proper spaced relation by inserting the spreaders 15 through the large portions of the key-hole slots 14 and then sliding the spreaders downwardly so that the neck portions 17 thereof will engage within the constricted portions of the key-hole slots. Obviously, the spreaders will operate to hold the members 11 in spaced parallel relation. It may be desirable to provide a transverse member 18 between the upper ends of the upright supports 11 as clearly indicated in order to provide a stronger bracing action.

For mounting the uprights 11 upon the floor B of the crib, use is made of angular brackets 19 which are nailed or otherwise secured upon the floor, as indicated at 20, and which are formed with arms 21 having grooves therein defining constricted neck portions 22 engaging within key-hole slots 23 at the lower ends of the uprights 11 as clearly indicated in Figure 4 of the drawings. Obviously, the key-hole slots at the lower portion of the members 11 must be

reversed with respect to the key-hole slots 14.

The ventilator structure further includes a plurality of superposed spaced horizontally extending strips 24 which simply rest 5 within the angular bracket members 13 as clearly indicated in the drawings.

Obviously, the ventilating structure may be easily mounted in position without the use of any securing devices other than the 10 spikes or nails 20 and it will therefore be apparent that but a small amount of time will be consumed in effecting installation.

In the operation, it is of course clear that the provision of the ventilating structure divides 15 the interior of the crib into any desired number of compartments, depending upon the number of ventilator structures employed, and within each compartment the corn or the like may be disposed with the 20 assurance that there will be ample ventilation afforded to permit proper drying out and seasoning without danger of rotting, molding or souring. It is really believed that the construction, operation and advantages 25 will be readily apparent to one skilled in the art without further explanation, though it might be mentioned that it is apparent that the device may be disassembled readily and stored in a compact form so as 30 to occupy but little space. This will also be of benefit during transportation.

While I have shown and described the preferred embodiment of the invention, it should be understood that I reserve the 25 right to make such changes in the form, construction and arrangement of parts as will not depart from the spirit of the invention or the scope of the subjoined claims.

Having thus described the invention, I claim:—

1. In a corn crib or the like, a ventilating structure comprising spaced pairs of uprights, means for mounting the uprights upon the floor of the corn crib or the like, spreader means connecting the uprights for maintaining them in spaced parallel relation, and a plurality of vertically spaced strips carried by the uprights, the uprights being provided with open topped angular bracket members for supporting said spaced strips.

2. A ventilating structure for a corn crib or the like, comprising spaced pairs of uprights, bracket means mounted on the floor of the corn crib or the like for supporting said uprights, spreader members detachably connected with the uprights for maintaining the same in spaced parallel relation, bracket members carried by the uprights, said bracket members having their upper ends open and vertically spaced strips carried by the bracket members and defining walls.

3. In a corn crib or the like, ventilating means comprising spaced pairs of uprights, each formed with keyhole slots and provided with outstanding angular brackets, spreaders having grooved end portions defining constricted necks engaged through and within the keyhole slots for maintaining the uprights in upright spaced parallel relation, and vertically spaced parallel strips arranged in horizontal position and engaged within said brackets for defining open walls.

In testimony whereof I affix my signature.

ERNEST B. NELSON.
